UNITED STATES PATENT OFFICE.

HALCOLM ELLIS, OF EAST ORANGE, NEW JERSEY.

REBOUNDING DEVICE FOR NUMBER-PRINTING MECHANISMS.

1,219,445.

Specification of Letters Patent. Patented Mar. 20, 1917.

Original application filed October 13, 1914, Serial No. 866,481. Patent No. 1,203,863, dated November 7, 1916.
Divided and this application filed October 9, 1916. Serial No. 124,673.

To all whom it may concern:

Be it known that I, HALCOLM ELLIS, a citizen of the United States, residing at East Orange, county of Essex, and State of New Jersey, have invented certain new and useful Improvements in Rebounding Devices for Number-Printing Mechanisms, of which the following is a specification.

This invention relates to rebounding devices for number printing mechanism, the present application being a division of Patent No. 1,203,863, dated Nov. 7, 1916.

My object is to provide improvements on the rebound device for the number printing mechanism disclosed in my Patents Nos. 1,197,276 and 1,197,277 dated September 5, 1916, and claimed in the latter patent.

In the mechanism of my patents aforesaid, the pivoted type sector is carried by an arm which is drawn to printing position by a spring. For effecting rebound of the type sector and the arm which carries it, there is provided a rebound spring device which constitutes the connection between a pivotally mounted rebound member and the arm and, being stronger than the spring first named, instantly retracts or rebounds the type sector after printing has occurred so that "chattering" of the type on the paper is prevented.

The rebound spring of the mechanism of my aforesaid patents is of peculiar form and relationship to the arm and the rebound member with which it co-operates.

My present invention has for its object the provision of a novel rebound device co-operating with the type-sector carrying arm and rebound member or piece in an improved manner whereby the peculiarly shaped spring of my aforesaid patents is entirely dispensed with and the single contractile coil spring serves, in connection with an improved pivoted member, to fulfil the two-fold function of drawing the arm, rebound member or piece, and type sector to printing position and for effecting automatic rebounding of the type sector and the arm which carries it, after the impression has been made on the paper carried by the platen, thereby preventing "chattering."

By dispensing with the peculiar rebound spring of my aforesaid patents, the cost of manufacture of the rebound device is re-

duced and liability of derangement or breakage of the rebound mechanism is obviated.

Combined with the contractile coil spring is a rocker which is pivoted to the arm which carries the type sector and has branches co-operating with different parts of the rebound member or piece. The action of the spring and points of co-action of the rocker with the rebound member are such that when the rebound member or piece is released by the disengagement of the printing trigger therefrom, the spring moves the arm and the rebound member or piece as a unit with the type sector to effect printing. Just prior to printing being effected, a stop engages with and arrests the rebound member or piece, whereupon the arm and the printing sector continue to advance by their momentum and printing is effected. This action causes the rebound rocker to disengage at one point from contact with the rebound member or piece. The spring still being under tension, it restores the rebound rocker to normal position, that is, with a two-point contact with the rebound member or piece, and, consequently, the arm and the type sector are instantly retracted or rebounded.

In the present application I have shown and described so much of the mechanism of the "Ellis" adding machine as will, in connection with the disclosures of my Patents 1,197,276 and 1,197,277 dated September 5, 1916, afford a thorough understanding of the application thereto, and operation, of the present invention. Those mechanisms which are set forth in the aforesaid patents are only described in a general way.

In the accompanying drawings:

Figure 1 is a vertical section showing parts of the machine in their normal position;

Fig. 2, a similar view showing the parts with one numeral key depressed, one accumulator engaged, and the printing mechanism set in position just prior to printing.

Fig. 3, a vertical detailed section of the number printing mechanism, the parts being in position for printing;

Fig. 4, a view similar to Fig. 3, showing the parts in rebounded position;

Fig. 5, a detail perspective of one of the type sectors, arm, rebound member or piece, rebound rocker, and setting link;

Fig. 6, a detail of the rebound member; Fig. 7, a detail of the arm; and Fig. 8 a detail of the rebound rocker.

General construction.—The machine is operated through suitable means, not shown, by a handle or motor acting on shaft O1.

Referring to Figs. 1 and 2, R50 is one of the racks, of which there are a plurality, said rack being guided by rod K3 and bar R92. The rack carries teeth 50R. The accumulators N45, which are shown like those in my Patent No. 1203863, dated Nov. 7, 1916, have gear wheels A50 adapted to be engaged with the racks 50R for purposes of addition, subtraction, or any other operation. The accumulators shown are for purposes of illustration only as they form no part of the present invention.

The racks R50 are controlled, as to extent of movement, to represent the numerical value of the respective numeral keys K51, K52, K53, K54, K55, K56, K57, K58, K59. Stops K23 carried by the key stem are adapted to coöperate with the steps on the rack R50.

Mounted on the shaft R1, is a three-armed lever R45, of which there are as many as the type sectors P54 and provided with the pins R15 and 15R. The third arm extends downward and has terminals to which is secured by pins R13, R14, a segmental rack R52. The pin R14 is received in a vertical slot in the lower edge of rack R50, shown by dotted lines in Figs. 1 and 2, so that backward or forward movement of the rack R50 causes rotation of the three-armed lever R45. A link P53 extends from pin 15R to pivot P10 in type sector P54. Type sector P54 is pivoted to arm 52P on pin P11 so that it can be swung outwardly or downwardly to bring it to the proper position for printing a number corresponding to the set position of the rack R50. The arm 52P is pivotally mounted on the rod P1.

To the shaft R1, there is secured a bail 45R which extends across the machine under the racks R50 and carries a bar R51. A spring R80 connects pin R13 to bar R51, there being as many of these springs as there are racks R50. An alining bar R93 carried by arms R44, secured to shaft R2, is adapted to enter the teeth of the segmental rack R52 just prior to the time when printing is to occur.

Rebound mechanism.—Pivotaly mounted on the rod P1 is the rebound member or piece P62 shown in detail in Figs. 5 and 6, this member being provided with teeth on one edge for engagement by the printing trigger 57P and the "O" printing trigger P57, the latter being spring-retracted and adapted to be released by the co-action of the pin R15 therewith. The printing trigger 57P is controlled and operated as set forth in my patents aforesaid.

Secured to the shaft P1 is a piece P58 across whose upper part extends a bar P17 adapted to engage and retain all the rebound members or pieces P62 until the printing operation is to be initiated.

A rebound bar P18, carried by arms P69, is adapted to serve as an abutment or stop for the rebound members or pieces P62. The bar P18 is rendered adjustable by an eccentric shaft P19 coöperating with arms P69.

On its inner edge the rebound member or piece P62 is provided with a tooth or projection P620 (Fig. 6).

My improved rebound rocker 58P which is shown in detail in Fig. 8, is pivoted to the arm 52P on a pin or stud P16 which passes through a hole P160 in said rocker, the rocker being carried bodily by the arm 52P. The rebound rocker 58P has a tooth or projection 580P which is engaged with the tooth or projection P620 and constitutes a heel on said rebound rocker. The toe 581P of the rocker is adapted to bear on the hub of the rebound member or piece P62 under normal conditions. The rebound rocker is of substantially the thickness of the flat rebound member P62 and the body of said rocker lies in front of the said rebound member. Each arm 52P carries a rebound rocker 58P and has as a companion a rebound member P62 so that each arm 52P and type sector P54 has its own rebound device or mechanism.

A contractile coil spring P85 is connected at one end to an eye 582P at the end portion of the shank of the rebound rocker 58P. There is a separate spring P85 for each rebound rocker.

It will be observed that the present rebound mechanism entirely dispenses with the peculiar rebound spring and stud employed in the rebound mechanism of my Patents 1,197,276 and 1,197,277; and with a single coil spring P85, in combination with the rebound rocker, performs the double function of advancing the printing mechanism to effect printing and to cause automatic rebounding after printing occurs.

Referring first to Figs. 1 and 5, the heel 580P is engaged with the tooth P620; and the toe 581P bears on the hub of the rebound member or piece P62. The spring P85 is under tension and maintains the parts in this condition. The rod P17 engages the rebound member P62 and the triggers 57P and P57 are engaged with the rebound member P62.

A key, K54 for instance, having been depressed and the handle or motor operated, as the machine goes through its cycle of operations, the parts first assume the position shown in Fig. 2 where the "O" trigger P57 is disengaged and the link P53 has set the type sector P54 so that a type corre-

sponding in numerical value to the key K54 will be in position to print, on further operation of the machine. Either or both of the accumulators N45 may be operated to cause engagement of the gear wheels A50 with the rack 50R for the performance of any operation desired such as addition, subtraction, or the taking of a total or subtotal, as will be clear from my aforesaid 10 patents.

The machine continuing its cycle of operations, the printing trigger 57P is released from the rebound member or piece P62, whereupon the spring P85 immediately 15 draws the arm 52P, rebound member P62 and rebound rocker 58P forward, as a unit, to effect printing on the paper carried by platen S as shown in Fig. 3. Just prior to the type sector P54 striking the paper on 20 the platen S, however, the rebound member P62 strikes the rebound bar P18, whereupon the momentum of the arm 52P and type sector P54 causes them to advance to effect printing. This action results in the 25 lifting of the toe 581P of the rebound rocker from the hub of the rebound member P62 as shown in Fig. 3, by reason of the fact that the rebound rocker 58P is bodily carried by the arm 52P. Immediately printing 30 has occurred, however, the tension of spring P85 asserts itself by turning the rocker 58P on its pivot P16 and restoring its toe 581P to contact with the hub of the rebound member P62 as shown in Fig. 4. This action 35 causes the arm 52P and type sector P54 to instantly rebound as shown in Fig. 4 and all chattering or double impression is thus prevented.

On completion of its cycle of operations, 40 the members are restored to the position shown in Fig. 1.

While the present rebound mechanism is particularly adapted for use on an Ellis machine, the claims are not to be considered 45 as thus limiting its use as the invention is well adapted for use on any printing device embodying a type carrier, and a rebound member or piece of the general construction and function of the piece P62. 50 I am also aware that modifications might be resorted to in the construction of the rebound rocker 58P and the exact manner in which it co-operates with the arm 52P and rebound member P62. Consequently, I do 55 not limit the invention to the precise construction hereinbefore set forth and shown in the drawings.

Having thus described my invention, what 60 I claim as new and desire to secure by Letters Patent, is:

1. In a printing mechanism, the combination with a type carrier, and a rebound member movably mounted in relation thereto, of a combined type carrier-actuator and rebounding device comprising a member 65

movably mounted on the type carrier and engaged with the rebound member, and spring means connected to said movably mounted member.

2. In a printing mechanism, the combination with a type carrier, and a rebound member movably mounted in relation thereto, of a combined type carrier-actuator and rebounding device comprising a rocker mounted on the type carrier and engaged with 70 the rebound member, and spring means co-operating with said rocker.

3. In a printing mechanism, the combination with a type carrier, and a rebound member movably mounted in relation thereto, of a combined type carrier-actuator and rebounding device comprising a rocker mounted on the type carrier and having a two-point engagement with the rebound member, and spring means co-operating with 85 said rocker.

4. In a printing mechanism, the combination with a type carrier, and a rebound member movably mounted in relation thereto, of a combined type carrier-actuator and rebounding device comprising a rocker mounted on the type carrier and having heel and toe portions engaged with different parts of 90 the rebound member, and spring means co-operating with said rocker.

5. In a printing mechanism, the combination with a type carrier, and a rebound member movably mounted in relation thereto, of a combined type carrier-actuator and rebounding device comprising a spring, and 100 a movable mechanical element constituting an operative connection between the spring and the type carrier and rebound member, said mechanical element being carried by one of said members and engaged with the other of them.

6. In a printing mechanism, the combination with a type carrier, and a rebound member movably mounted in relation thereto, of a combined type carrier-actuator and rebounding device comprising a spring, and a movable mechanical element constituting an operative connection between the spring and the type carrier and rebound member, said mechanical element being carried by one of 110 said members and having a two-point engagement with the other of them.

7. In a printing mechanism, the combination with a type carrier, and a rebound member movably mounted in relation thereto, of a combined type carrier-actuator and rebounding device comprising a spring, and a rocker constituting an operative connection between the spring and the type carrier and rebound member, said rocker being 120 pivotally carried by one of said members and having oppositely extending heel and toe portions respectively engaging different parts of the other member.

8. In a printing mechanism, the combina- 125

tion with a type carrier, and a rebound member movably mounted in relation thereto, of a combined type carrier-actuator and rebounding device comprising a spring having one end anchored, a rocker constituting an operative connection between the spring and the type carrier and rebound member, said rocker being pivotally carried by one of said members and having oppositely extending 5 heel and toe portions respectively engaging

different parts of the other member, and means for arresting the movement of the rebound member after it has been advanced by the spring, said type carrier thereupon advancing to effect printing and being immediately rebounded by the combined action of the spring and the rocker aforesaid. 15

In testimony whereof, I hereunto affix my signature.

HALCOLM ELLIS.
